UNITED STATES PATENT OFFICE.

FREDERICK K. WRIGHT, OF SYRACUSE, NEW YORK, ASSIGNOR TO R. E. DIETZ COMPANY, OF NEW YORK, N. Y.

LANTERN.

No. 895,132.

Specification of Letters Patent.

Patented Aug. 4, 1908.

Application filed September 3, 1907. Serial No. 391,890.

To all whom it may concern:

Be it known that I, FREDERICK K. WRIGHT, a citizen of the United States, residing at Syracuse, in the county of Onondaga and 5 State of New York, have invented a new and useful Improvement in Lanterns, of which the following is a specification.

This invention relates to loops, staples, bearings, posts and similar fixed parts which 10 are used in lanterns for confining or guiding movable parts, for instance, to the guide loops or staples which are secured to the side tubes of tubular lanterns for confining and guiding the upright wires or rods of 15 the vertically movable globe frame or support, to the bearings in which the lifting levers are journaled, and to the posts which project upwardly from the base portion of the lantern and enter an opening in the detachable globe plate for preventing the latter 20 from turning on the burner. These loops and other devices have usually been secured to the tubes by soldering.

The object of this invention is to secure 25 such devices to the tubes or other supports by more durable and reliable means and without requiring the expensive operation of soldering.

In the accompanying drawings; consisting 30 of two sheets: Figure 1 is an elevation of a tubular lantern in which the guide loops are secured to the tubes by this invention. Fig. 2 is a fragmentary inside elevation of one of the tubes preparatory to applying the guide 35 loop thereto. Fig. 3 is a fragmentary sectional elevation of the tube with the guide loop applied thereto. Fig. 4 is a horizontal section in line 4—4, Fig. 3. Fig. 5 is a perspective view of the guide loop. Fig. 6 is a 40 perspective view, showing another construction of guide loop embodying the invention. Fig. 7 is a horizontal section of the loop shown in Fig. 6. Fig. 8 is a vertical section, showing another construction of guide loop 45 embodying the invention. Fig. 9 is a horizontal section in line 9—9, Fig. 8. Fig. 10 is a fragmentary horizontal section, showing another construction of guide loop embodying the invention. Fig. 11 is a perspective 50 view of this loop. Figs. 12 and 13 are fragmentary vertical sections in lines 12—12 and 13—13, Fig. 10, respectively. Fig. 14 is a fragmentary elevation, showing the bearing 55 of the lifting lever secured to the tube by this invention. Fig. 15 is a vertical section

in line 15—15, Fig. 14, on an enlarged scale. Fig. 16 is a fragmentary sectional elevation, showing a post on the lower air chamber secured by this invention.

Like reference characters refer to like parts 60 in the several figures.

A represents the side tubes forming part of the rigid frame of a tubular lantern and B the upright side wires or rods forming part of the globe frame which is movable vertically in the rigid lantern frame in a well known manner.

C represents the guide loops which are secured to the inner sides of the tubes and project inwardly therefrom for confining and 70 guiding the upright wires or members B of the globe frame. These guide loops are provided for attachment to the upright tubes or members of the lantern frame with barbed attaching shanks which are passed through 75 openings or slots in the inner wall of the tube or supporting member. The barb is flexible and forced out of its normal position in inserting the shank into the opening of the frame and returns to its normal position 80 after it has cleared the opening, whereby the barbed shank assumes a position in which it secures the loop to the tube or support against withdrawal or accidental detachment. These barbed attaching shanks may be constructed in various ways, some of which are 85 illustrated in the drawings.

In the construction represented in Figs. 2—5, the guide loop is provided at each end with attaching shanks 20 which are bent 90 back upon themselves to form barbs 21 and the loop is provided, preferably above and below each shank, as shown, with shoulders 22 which limit the inserting or forward movement of the shank. The tube or 95 support is provided for the reception of the attaching shanks with upright slots 23 which are so narrow that in inserting the barbed shanks into the slots the barbs are pressed out of their normal position 100 toward the shanks. When the rear ends of the barbs have cleared the slots the barbs spring back to their normal position and engage against the interior side of the inner wall of the tube, as represented in 105 Fig. 4. The shoulders 22 at the base of the shanks bear against the exterior side of the inner wall and prevent further movement of the loop in the inserting direction and the barbs bearing with their rear ends 110

against the interior side of the inner wall prevent movement in the opposite direction. The loop is secured in this manner to the tube simply by inserting the barbed shanks 5 into the slots thereof and without requiring any special soldering for that purpose.

In the construction represented in Figs. 6 and 7, the barbs 24 are formed on the shanks 25 by slitting the latter and bending 10 the barbs outwardly.

In the construction represented in Figs. 8 and 9, the barbs 26 are formed on the shanks 27 in the manner shown in Figs. 4 and 5 by bending the shanks back upon 15 themselves, but instead of forming stop shoulders at the bases of the shanks, as in the construction represented in Figs. 4 and 5, the shoulders are omitted and the shanks are made so long that they stop against the 20 outer wall 28 of the tube when the shanks have been inserted. In this position of the parts the shanks are held against further forward movement by their ends bearing against the outer wall of the tube and 25 against backward movement by the barbs.

In the construction represented in Figs. 10—13, each shank 29 is provided with two barbs 30 formed at the upper and lower sides of the shank and tapering forwardly, 30 so that each barbed shank has approximately the form of an arrow head. The barbs are bent so as to stand normally at a slight angle to the plane of the shank. In inserting the shanks into the upright slots 35 31 in the tubes the barbs are deflected out of their normal position by the side walls of the slots, and when the barbs have cleared the slots they spring back to their normal position and lock the loop to the 40 tube.

The loops and their barbed shanks are made of sheet brass, tinned sheet steel or other suitable material possessing the necessary flexibility and elasticity.

In the construction represented in Figs. 45 14 and 15, the bearing 32 in which the lifting lever 33 is journaled is secured to the tube by barbed shanks 34.

In the construction represented in Fig. 50 16, the post 35, which enters in a well known manner an opening in a detachable

globe plate 36 for holding the latter against turning, is secured to the top plate 37 of the lower air chamber by barbed shanks 38.

I claim as my invention:

1. The combination with a supporting tube provided with a slot, of a loop having a barbed attaching shank which projects into said tube through said slot and bears with its barb against the inner side of said tube, said loop being provided with means for arresting its inserting movement when the barb has engaged against the inner side of the tube, substantially as set forth. 60

2. The combination with a supporting 65 tube provided with slots, of a loop or staple having barbed attaching shanks which project into the tube through said slots and which bear with their barbs against the inner side of the tube, said loop or staple being provided with means for arresting its inserting movement when the barbs have engaged against the inner side of the tube, whereby the loop or staple is rigidly secured to the tube, substantially as set forth. 70

3. The combination with a supporting tube provided with slots, of a loop or staple having barbed attaching shanks which project into the tube through said slots and which bear with their barbs against the 80 inner side of the tube, said loop or staple being provided with stop shoulders which bear against the outer side of the tube, substantially as set forth.

4. The combination with a lantern frame 85 having an upright tube provided with slots, and a globe support vertically movable in said frame along said tube, of a guide loop for said support having barbed attaching shanks which project into the tube through 90 said slots and bear with their barbs against the inner side of the tube, said guide loop being provided with means which limit its inserting movement, whereby said guide loop is rigidly secured to said tube, substantially as set forth. 95

Witness my hand in the presence of two subscribing witnesses.

FREDERICK K. WRIGHT.
